DEHYDRATING APPARATUS

Henry C. French, Elm Grove, Wis., assignor to
 Arnold Dryer Co., Milwaukee, Wis., a corpora-
 tion of Wisconsin

Application February 7, 1941, Serial No. 377,798

17 Claims. (Cl. 263—32)

This invention relates to improvements in dehydrating apparatus.

It is a general object of the present invention to provide an improved dryer which can be furnished in such size as to be portable, and which will efficiently handle large quantities of forage crops or the like and rapidly and continuously dry such material with a minimum loss of nutrients and color and with a minimum expense for fuel.

A more specific object of the invention is to provide an efficient dryer of the class described embodying a rotatable cylinder wherein the combustion chamber is rotatable with said cylinder and effectively supported therein on longitudinal spacers forming a combustion chamber pocket.

A further object of the invention is to provide an improved dryer having means for admitting air in regulated quantities into the mixing chamber through passageways extending longitudinally of the combustion chamber on the exterior thereof and between the longitudinal combustion chamber supporting spacers.

A further object of the invention is to provide in a dryer having a rotatable cylinder with a combustion chamber therein, means for returning hot gases of combustion together with steam from the exhaust outlet of the apparatus to the mixing chamber, the arrangement being such that said returned steam is superheated before being discharged into the mixing chamber. Thus economy in operation is effected because of reclaiming the used gases of combustion. Furthermore, superheated steam is a more efficient drying medium than air, and the re-circulation of said steam eliminates the necessity of admitting free air in as large quantities as would otherwise be required, and thereby reduces the oxygen content in the dryer.

A further object of the invention is to provide apparatus as above described wherein the admission of used gases and steam to the mixing chamber is through a common passageway with the free air and under the control of the air admission regulator, the arrangement being such that the amount of used gases and steam admitted is inversely proportional to the amount of free air.

Other objects of the invention are to provide a dryer wherein the hot gases of combustion are introduced into one end of the apparatus and the material to be dried is introduced from the opposite end into the current of hot gases; wherein the introduction of material to be dried may be performed by a positive screw feed;

wherein the housing for the screw feed rotates with the cylinder and has a slip joint connection with the material receiving hopper; wherein there are a number of intercommunicating, concentric cylinders with spiral baffles arranged on the outer surfaces of the inner cylinders to most effectively advance the material and agitate the air circulating in each cylinder; wherein there are lineal conveyor flights on the inner surface of the cylinders; wherein the outer cylinder is effectively insulated against loss of heat; wherein the concentric cylinders are effectively connected and spaced by means of radial straps or the like; and wherein the outer cylinder is formed with circumferential tracks cooperable with flanged rollers on the supporting structure or carriage to effectively support the cylinder for rotation.

With the above and other objects in view, the invention consists of the improved dehydrating apparatus and all its parts and combinations, as set forth in the claims, and all equivalents thereof.

In the accompanying drawings illustrating one complete embodiment of the preferred form of the invention, in which the same reference numerals designate the same parts in all of the views,

Fig. 1 is a side elevational view of the improved apparatus, parts being broken away, and part of the apparatus being shown in longitudinal section;

Fig. 2 is a view of the combustion chamber end of the apparatus, part of the cylinder being broken away and shown in transverse section;

Fig. 3 is a sectional view taken on the line 3—3 of Fig. 1;

Fig. 4 is a side elevational view of the piping arrangement for handling the exhaust gases, including the dry material collector, part of the associated dryer apparatus being shown in dot-and-dash lines;

Fig. 5 is a front view on an enlarged scale of the mechanism for admitting regulated quantities of free air and exhaust gases;

Fig. 6 is a fragmentary sectional view taken on line 6—6 of Fig. 5; and

Fig. 7 is an edge view of a portion of the structure shown in Fig. 5, with the exhaust gas hood and outer band omitted.

Referring more particularly to the drawings, the numeral 10 designates the frame of a suitable supporting structure, which preferably takes the form of a carriage having front wheels 11 and rear wheels 12 whereby the dryer is readily port-

able. Depending from the front of the frame 18 is a support 13 for a fifth wheel 14, whereby the front axle 15 is suitably supported for steering movement. The front axle 15 is relatively short so as to clear the drop frame portion 16 to the rear thereof during steering movement.

The supporting frame 10 is equipped with a pair of flanged rollers 17 on each side, the rollers being keyed to a shaft 18 which is journalled in bearings 19. The rollers 17 cooperate with circumferential drive bands 20 on the outer side of an outer cylinder or drum 21. The drum may be rotated by transmitting rotation of one of the roller shafts 18, or in any other desired manner.

Arranged in spaced relation from each other and from the outer drum 21 are inner concentric drums 22 and 23. At one end of the apparatus the drums are connected to each other and suitably spaced by means of radial straps 24. The outer ends of these straps are braced against and suitably connected to lineal conveyor flights 25 and 26 on the inner surfaces of the outer and intermediate drums, as indicated at 27. The inner ends of the straps are flanged and connected to the outer surface of the adjacent drum, as at 28. At the other end of the apparatus there is a housing 30 for a spiral conveyor feed 31. The housing 30 extends axially of the drums 22 and 23 through the end opening 32 of the intermediate drum where it is welded to the edges of said opening, and into the open end of the inner drum 23. The drum 22 is connected to the drum 21 by a plurality of radially extending gussets 33 and a plurality of radially extending gussets 33' on the inside of the drum 22 support a ring 29 within which the end of the innermost drum 23 is slidably supported. In addition a conical discharge guide 34 connects the exterior of the spiral conveyor housing 30 with the end of the intermediate drum 22 to firmly support the conveyor housing. The conical discharge guide directs material being discharged from the outer drum toward the end discharge opening 35 in said drum.

Wet material to be dried, which material has previously been cut to desired length, is introduced by any suitable means into a hopper 36, which hopper is suitably supported on the frame 10. The bottom of the hopper communicates with an opening 37 in a fixed housing portion 38 for the spiral feed conveyor 31. The conveyor housing portion 38 is secured to and rotatable with the drying drums, and there is a slip joint 39 between the outer end of the rotatable housing portion 38 and the inner end of the fixed housing portion 38.

The spiral conveyor 31 is driven in any suitable manner, such as by an endless chain 40 extending from a suitable source of power and cooperating with a sprocket 41 on the outer end of the conveyor shaft. The wet material is therefore conveyed by the spiral conveyor through the housings 38 and 30, with the material forming a seal against the admission of air through the conveyor housing. The material is discharged radially of the inner drum 23, as indicated by the arrow in Fig. 1, from between the supporting arms 42 of a spider 43, which spider has an asbestos shield as at 44.

At the opposite end of the apparatus the innermost drum has secured to its inner surface longitudinally extending circumferentially spaced I-beams or spacers 44 which form a pocket for slidably receiving a combustion chamber forming cylinder 45. This cylinder may be con-

structed of refractory material or heat resisting metal such as cobalt steel. The I-beams 44 provide longitudinal spaces or passageways 46 exteriorly of the combustion chamber, which serve to cool the latter and also form ducts for the admission of free air and returned gases and steam, as will hereinafter be described. The steam in passing through the passageways 46 becomes superheated before being discharged into the mixing chamber 47.

The inner end of the combustion chamber is open, as at 48, so that the hot gases of combustion are discharged into the mixing chamber 47. The outer end of the combustion chamber 15 is formed with a relatively small inwardly flared opening 49, which is in registration with the nozzle 50 of an oil burner 51 or other suitable source of heat.

The oil burner nozzle 50 extends axially into the open end of a cup-shaped member 52, said member having its inner end secured to the outer end of the combustion chamber 45 and having an opening 53 in registration with the flared opening 49 (see Fig. 6). Spaced outwardly from 25 and concentric with respect to the peripheral wall 54 of the cup-shaped member 52 is a ring 55 having external circumferential flanges 56 (see Figs. 6 and 7). The ring 55 is secured to the end wall of the outer drying drum as at 30 57. Thus an annular space 58 is formed between the ring 55 and the peripheral wall 54, which space is in registration with the passageways 46 surrounding the combustion chamber. Free air may be admitted to the annular space 58 35 through ports 59, which ports can be closed completely or opened to a desired extent by means of a ring damper 60 having ports 61 which may be made to partially or completely register with the ports 59. The damper ring may be held in 40 adjusted position by bolts 62 cooperable with arcuate slots 63.

The assembly of the cup-shaped member 54, ring 55, and combustion chamber cylinder 45 is therefore rotatable with the drying drums and 45 some of the peripheral openings 64 in the ring 55 are always in registration with the curved lower end of a hood 65. The lower end of the hood has flanges 66 (see Fig. 6) which fit between the flanges 56 of the ring 55. The openings 50 64 in the ring 55, which are not in registration with the hood, are always closed by a band 67 which has its ends bolted to the ends of the hood as at 68. The band 67 also fits between the flanges 56 of the ring 55.

With this construction, used gases and steam which are returned through the pipe 69 enter 55 the hood 65 and pass through the openings 64 into the annular space 58, and from the space 58 through the longitudinal passageways 46 around the combustion chamber into the mixing chamber. When the circular damper 60 is in the 60 position of Fig. 5, free air from the outside will also be admitted. The wider the damper 60 is open to admit free air, the less flue gases and steam which will be drawn through the hood 65. Conversely, by limiting the size of the air openings, or by closing the same entirely through 65 adjustment of the damper 60, a greater amount of flue gases and steam will be drawn into the mixing chamber of the dryer.

The movement through the drums is created by the action of a suitably driven exhaust fan 70 mounted in a housing 71, which housing has an opening 72 communicating with the conduit 73. The conduit 73 has its upper end surround-

ing the housing 30 for the spiral conveyor and extending horizontally into the discharge opening 35 of the outer drum 21, the drum being rotatable around said portion of the conduit 73.

When the blast of hot gases entering the combustion chamber 45 from the nozzle 50 together with air drawn in around the nozzle, as indicated by the arrows in Fig. 1, is discharged into the mixing chamber 47, it is mixed with free air, used gases of combustion, and steam, which enter the mixing chamber 47 from the passageways 46 surrounding the combustion chamber. If the air damper 60 is shut off completely, only used gases and steam will enter from the passageways 46. The steam as it passes through the passageways 46 is superheated, and the used gases are additionally heated; also the temperature of any free air admitted is raised substantially before said air is discharged into the mixing chamber. This passage of gases, steam, and free air through the passageways 46 also tends to keep down the temperature of the combustion chamber cylinder 45. Into this mixture of gases the wet material to be dried is discharged radially, as indicated by the arrow in Fig. 1, from the periphery of the spider 43. In the rotation of the inner drum particles of material to be dried which drop to the bottom of the drum are carried by the lineal flights 74 to the top of the drum where they fall through the blast of hot gases. The lighter particles will be advanced through the drum by the blast of gases more rapidly than will the heavier particles. The gases and partially dried material pass out of the discharge end of the inner drum 23 and into the space between said inner drum and the intermediate drum 22. This movement is caused by the action of the exhaust fan. The outer surface of the inner drum 23 is provided with spiral baffles 75 which serve to mechanically advance the material and also cause the gases to be agitated in the space between the cylinders to more effectively extract moisture from the material. The heavier particles of material between the drums 22 and 23 will fall to the bottom of the drum 22 and be lifted by the lineal flights 26. These flights will carry the material upwardly as the drum rotates, to again drop the material into the stream of hot gases. From the discharge end 76 of the intermediate drum the gases and material pass into the space between the outer drum 21 and intermediate drum 22 and travel in a reverse direction, as indicated by the arrows. While traveling through the outer drum the material and gases are acted upon by the spiral baffles 77 on the outer surface of the intermediate drum 22 and by the lineal flights 25. The stream of gases and material is ultimately directed by the conical discharge guide 34 into the passageway 73 where it passes through the fan housing 71 and out through a discharge pipe 78.

The discharge pipe 78 communicates with a collector 79 (see Fig. 4), and arranged concentrically within the collector is a cylinder 80 which is open at the top, as at 81, and also at the bottom, as at 82. The material and gases first pass in a circular path around the cylinder 80 and the dried material falls out of the bottom of the collector 79 into a suitable receptacle. The used gases pass into the lower end 82 of the cylinder 80, and some of said gases are discharged out of the upper end 81. A certain amount of these gases and steam, depending upon the position of the air regulator 60 (see Fig. 5), is re-circulated through the conduit 69 to the hood 65 to be

directed back into the dryer as heretofore explained.

From the above it is clear that a relatively inexpensive, portable dryer has been provided wherein the combustion chamber is contained within and is rotatable with the dryer cylinders. Novel means is also provided for admitting free air and returned gases and steam to the dryer through passageways on the exterior 10 of a rotating combustion chamber. The method of introducing the wet material into the dryer provides a seal, formed by the material itself, against admission of undesired free air, and the material is discharged in a radial direction into the mixing chamber in a position to be most effectively acted upon by the hot gases. By having the feed hopper at the same end of the dryer as the discharge, a thermometer 83 may be used at the outlet passageway 35 so that the 15 machine may be fed by watching the temperature of the exhaust gases which are being discharged to thereby permit operation of the dryer at maximum efficiency. By recirculating part of the exhaust gases and outlet steam, there is 20 economy in operation and it is unnecessary to take in as much free air.

The improved dryer is very effective in handling alfalfa and other forage crops, and due 25 to its portability it can be moved into the field where the cutting is being performed to dry the hay while it is still fresh and green, and before it has had an opportunity to become wilted by exposure. The structure of the apparatus is 30 such that the hay is subjected to the proper amount of heat so that it is dried quickly, uniformly, and economically with a minimum loss of nutrients and color.

In the claims the term "gases" as used to define the matter directed through the passageways 44 adjacent the exterior of the combustion chamber contemplates not only used gases of combustion but also any of the other gases directed through said passageways such as air, 35 steam, or any combination of said gases.

While the use of a plurality of concentric drums is highly desirable, many of the features of this invention are obviously applicable to dryers comprising a single drum only and, therefore, while only one form of construction has 40 been shown and described, various changes and modifications may be made without departing from the spirit of the invention, and all of such changes are contemplated as may come within 45 the scope of the claims.

I claim:

1. In a dehydrating apparatus, a rotatable drying drum, a combustion chamber unit extending into one end of said drum and rotatable therewith, means for delivering hot gases of combustion into said rotatable combustion chamber, said drum having an intermediate mixing chamber into which hot gases of combustion are discharged from the combustion chamber, means including passageways extending adjacent the exterior of the combustion chamber unit for directing gases into said mixing chamber beyond the combustion chamber unit, means for feeding wet material into said mixing chamber from the opposite end of said drum to be acted upon by the hot gases therein, and means for discharging dried material.

2. In a dehydrating apparatus, a rotatable drying drum, a combustion chamber unit extending into one end of said drum and rotatable

therewith, means for delivering hot gases of combustion into said rotatable combustion chamber, said drum having an intermediate mixing chamber into which hot gases of combustion are discharged from the combustion chamber, means including passageways extending adjacent the exterior of the combustion chamber unit for directing free air and used gases directly into said mixing chamber, means for feeding wet material into said drum to be acted upon by the hot gases therein, and means for discharging dried material.

3. In a dehydrating apparatus, a rotatable drying drum, a combustion chamber unit extending into one end of said drum and rotatable therewith, means for delivering hot gases of combustion into said rotatable combustion chamber, means for intercepting used gases of combustion, means including passageways extending adjacent the exterior of the combustion chamber unit and substantially surrounding the same for directing said re-circulated gases which have already acted upon material back into said dryer beyond the combustion zone, means for feeding wet material into said drum to be acted upon by the hot gases therein, and means for discharging dried material.

4. In a dehydrating apparatus, a rotatable drying drum, a combustion chamber unit extending into one end of said drum and rotatable therewith, said drum having a mixing chamber inwardly of said combustion chamber unit, means for delivering hot gases of combustion into said rotatable combustion chamber, means for re-circulating gases which have already acted upon the material, means for directing said gases back into the mixing chamber of the dryer, while the latter is rotating and beyond the inner end of the combustion chamber, means for feeding wet material into said dryer to be acted upon by the hot gases therein, and means for discharging dried material.

5. In a dehydrating apparatus, a rotatable drying drum, a combustion chamber unit extending into one end of said drum and rotatable therewith, means for delivering hot gases of combustion into said rotatable combustion chamber, means including passageways extending adjacent the exterior of the combustion chamber unit for directing used gases including steam back into said dryer and for discharging said gases inwardly of the combustion zone, whereby the steam is superheated by contact with the combustion chamber unit before being discharged, means for feeding wet material into said drum to be acted upon by the hot gases therein, and means for discharging dried material.

6. In a dehydrating apparatus, a rotatable drying drum, a combustion chamber unit extending into one end of said drum and rotatable therewith, means for delivering hot gases of combustion into said rotatable combustion chamber, a screw feed conveyor including a tubular housing portion, said conveyor and housing extending into the opposite end of the drum and the housing being rotatable therewith for delivering wet material into the stream of hot gases within the drum, an external feed hopper, said rotatable tubular housing portion having a slip joint connection with said hopper, and means for discharging dried material from the drum.

7. In a dehydrating apparatus, a rotatable drying drum, a combustion chamber unit ex-

tending into one end of said drum and rotatable therewith, means for delivering hot gases of combustion into said rotatable combustion chamber, means for delivering wet material into the opposite end of the drum to be acted upon by the hot gases therein, and means at said end of the drum for discharging dried material and used gases.

8. In a dehydrating apparatus, an outer rotatable drum, at least one smaller drum within said outer drum and communicating therewith, said smaller drum being rotatable with said outer drum, means for delivering hot gases into one of said drums, an end of said outer drum having a discharge opening, a screw feed conveyor including a tubular housing portion extending into said discharge opening of the outer drum and into an end of an inner drum therein, external means for rotatably supporting the outer end of said tubular housing portion, means for supporting said housing portion for rotation with the drums, means providing an outlet from said smaller drum around said tubular housing portion, and means for discharging dried material from the outer drum around said tubular housing portion.

9. In a dehydrating apparatus, an outer rotatable drum, a smaller drum within said outer drum and rotatable therewith to provide a passageway between the inner and outer drums, means for delivering hot gases into the inner drum, means for delivering wet material into said inner drum, baffles on the exterior of said inner drum shaped to agitate gases and material passing between the drums and to aid in the advancement of said gases and material, and means for discharging the dried material.

10. In a dehydrating apparatus, an outer rotatable drum, a smaller drum within said outer drum and rotatable therewith to provide a passageway between the inner and outer drums, means for delivering hot gases into the inner drum, means for delivering wet material into said inner drum, spiral baffles on the exterior of said inner drum shaped to agitate gases and material passing between the drums and to aid in the advancement of said gases and material, and means for discharging the dried material.

11. In a dehydrating apparatus, an outer rotatable drum, a smaller drum within said outer drum and rotatable therewith to provide a passageway between the inner and outer drums, means for delivering hot gases into the inner drum, means for delivering wet material into said inner drum, baffles on the exterior of said inner drum shaped to agitate gases and material passing between the drums and to aid in the advancement of said gases and material, lineal flights on the inner surface of the outer drum for lifting material during the rotation of the drum and for dropping the same into the current of gases and onto the exterior of the inner drum to be acted upon by the baffles, and means for discharging dried material from the drum.

12. In a dehydrating apparatus for forage crops or the like a rotatable drying drum having a combustion zone portion adjacent one end and within the drum, means for delivering hot gases of combustion into said combustion zone portion, said drum having a mixing chamber portion inwardly of said combustion zone portion, means for feeding wet material into said drum at a location other than the combustion zone portion, means including passageways

extending adjacent the exterior of the combustion zone portion for directing gases having a reduced oxygen content into said mixing chamber portion inwardly of the combustion zone portion, said passageways being positioned and arranged to provide for substantial cooling of the combustion zone portion by the gases moving through said passageways and said gases being subsequently utilized for increasing the drying efficiency, means for feeding wet material into said drum to be acted upon by the hot gases therein, and means for discharging the dried material.

13. In a dehydrating apparatus for forage crops or the like, a rotatable drying drum having a combustion zone portion adjacent one end, means for delivering hot gases of combustion into said combustion zone portion, said drum having a mixing chamber portion inwardly of said combustion zone portion, means for feeding wet material into said drum at a location other than the combustion zone portion, an exhaust fan for creating a current of drying gases to convey the material through said drum, and means for admitting gases in addition to those from the combustion zone to said mixing chamber inwardly of the combustion zone to supply gases for said current.

14. In a dehydrating apparatus, a rotatable drying drum, a combustion chamber unit extending into one end of said drum and rotatable therewith, means for delivering hot gases of combustion into said rotatable combustion chamber, means including passageways extending adjacent the exterior of the combustion chamber unit for directing gases into said dryer beyond the combustion chamber unit, said passageways being positioned and arranged to provide for substantial cooling of the combustion chamber by the gases moving through said passageways, means for feeding wet material into said drum to be acted upon by the hot gases therein, and means for discharging dried material.

15. In a dehydrating apparatus, a rotatable drying drum, a combustion chamber unit extending into one end of said drum and rotatable therewith, means for delivering hot gases of combustion into said rotatable combustion chamber, means including passageways extending adjacent the exterior of the combustion chamber unit for directing gases into said dryer beyond the combustion chamber unit, said combustion chamber unit being substantially surrounded by said passageways to provide for substantial cooling of the combustion chamber by the gases moving through said passageways, means for feeding wet material into said drum to be acted upon by the hot gases therein, and means for discharging dried material.

16. In a dehydrating apparatus, a rotatable drying drum, means for delivering hot gases of combustion into one end of said rotatable drum, a screw feed conveyor including a tubular housing portion, said conveyor and housing portion extending into the opposite end of the drum and the housing being rotatable therewith for delivering wet material into the stream of hot gases within the drum, an external feed hopper, said rotatable tubular housing portion having a slip joint connection with said hopper, and means for discharging dried material from the drum.

17. In a dehydrating apparatus, a rotatable drying drum, means for delivering hot gases of combustion into one end of said drum, means for delivering wet material into the opposite end of the drum to be acted upon by the hot gases therein, means at said last mentioned end of the drum for discharging dried material and used gases, and a thermometer at said last mentioned end of the drum subjected to the temperature of the used gases being discharged and positioned to be visible while the wet material is being delivered into the same end of the drum.

HENRY C. FRENCH.
